FORNIA

ELECTROMAGNETIC SOUND REPRODUCER

Application filed March 29, 1928. Serial No. 265,599.

My invention relates broadly to electromagnetic sound reproducers and more specially to radio broadcast reception.

This invention is the outcome of the desire 5 to provide a more faithful reproduction of a "broadcast" than has been hitherto obtainable, particularly in relation to the broadcasting of music.

I am a maker of fine violins, and in my 10 present invention have adapted acoustic elements and principles that are embodied in the old masterpieces of Cremona, such as the thicknesses of the wood employed, the location of the soundposts with relation to the 15 bridges, and others that will appear.

It should be borne in mind that loudspeakers, like violins, go to all parts of the world and have to function under widely differing ranges of temperature, with consequent expansion and contraction for 20 which adjustment means should be provided.

My loud-speaker is preferably a four stringed instrument, so to speak, that is capable of reproducing the whole of the 25 musical scale by vibration of tape-like steel armatures adapted to respond to tones of different pitch and thus give full, undistorted reproduction of the tones as broadcasted.

An object of my invention is to provide a 30 loud-speaker instrument for radio broadcast reproduction that is extremely sensitive to radio frequencies, that is free from conflicting acoustic eddies and whose elements combine to reproduce all the tones of the musical scale.

35 A further object is to provide in a loud-speaker instrument a plurality of magnetic drivers adapted to actuate a plurality of companion armatures each being adapted to respond to tones of different pitch.

40 Another object is to provide a loud-speaker instrument having a plurality of independent compensating armatures, each of which is adapted efficiently to reproduce affinitive portions of the entire range of musical 45 frequencies when appropriately driven.

Still another object is the provision of a plurality of steel-tape armatures of varying cross-sectional areas and bridge support means therefor.

50 Another object is to provide a loud-speaker

instrument wherein a resonant body carries a plurality of posts in fixed relation thereto, the posts carrying strained armatures and being braced by interrelated spacing means, said means being adapted to carry magnetic driving units. 55

A further object is the provision of regulatory adjustment means relative to said magnets and said armatures.

Another object is to provide bracing means 60 for the upper ends of the posts.

Another object is to provide tripodal regulatory means adapted to secure nice adjustment between said individual magnet and its 65 companion armature.

These objects are obtained generally by the form, material and construction of the parts employed, together with other objects and advantages that will hereinafter appear. 70

In the drawings:—

Figure 1 is a plan view of my invention.

Fig. 2 is a sectional elevational view taken on the line 1—1 of Fig. 1.

Fig. 3 is a plan of a magnet base.

Fig. 4 is a sectional elevational view taken 75 on the line 11—11 of Figure 3.

Fig. 5 is a detached plan view of a tripodal magnet adjuster.

Fig. 6 is a detail of an adjustment means.

Fig. 7 shows two views of a lock-washer. 80

Similar reference characters denote similar parts throughout the several views.

Referring to the drawings in detail, reference character 1 denotes the resonant body as a whole, comprising the bottom 2, sides 3 and top 4, all of suitable seasoned wood and glued together so as to form a resonant soundbox; the top 4 being provided with the sound-hole 5, and vertically disposed within said box are the sound-posts 6 whose approximate location within said box is indicated by the dotted lines in Fig. 1. 85

At regular intervals apart around the periphery of the body 1 and in fixed relation thereto are the vertically disposed strain posts 7, 7^a, 7^b, 7^c, 7^d, 7^e, 7^f and 7^g which extend upwardly above the top 4 for a suitable distance so as to carry the armature members 8, 8^a, 8^b and 8^c at their proper relative heights above the respective magnets 9, 9^a 95 100

and 9°, said posts being linked together by the braces 15.

Spaced between the posts 7 and 7^a at a suitable distance above said top 4 is the horizontally disposed outer rail 10 which is preferably tenoned into a mortice as indicated in dotted lines 10°, there being similar rails 10^a, 10^b and 10^c similarly secured to their respective posts 7^b—7^c, 7^a and 7^c and 7^b—7^c; whereas, said rails 10 and 10^b are suitably morticed to receive the tenoned ends of the inner rails 11—11 which are carried by said rails 10 and 10^b with all their surfaces flush; whilst the inner rails 11—11 are suitably morticed to accommodate the tenoned ends of the inmost rails 12—12; all the said rails lying in the same horizontal plane.

The peculiar arrangement of said rails provides what might be called "timbers" for carrying the said magnets, in a manner now to be described, and as all said magnets are alike, and mounted alike, a description of one will suffice for all:

A base member (Fig. 3) is first attached to the respective rails 10—12 at the location shown in Fig. 1 by means of the wood-screw 25^a which by passing through the hole 25 secures said base to the rail 10.

In this position the downwardly-extending lug 24^a engages the inner side of the rail 12 to which it is snugly and firmly secured by the wood-screw 26^a that passes through the hole 26 and is driven home into the wood.

It should be understood that each magnet element as 9 is provided on the underside thereof with the V-shaped member 19 (Fig. 5) which is secured in fixed relation to said magnets by the screws 20 that pass through suitable perforations in the magnets and make threaded engagement with the suitably-threaded holes 21—21—21. Said V-shaped member being preferably of brass or other non-magnetic material and being provided adjacent the free ends and adjacent the apex thereof with the holes 22—22—22 that are adapted to accommodate the screw adjustment means 23—23—23 which in turn have a lower threaded portion adapted to make screw thread engagement with the complementary means 24—24—24 of the base member, Fig. 3, in the manner well known in detail in Fig. 6, or in other suitable manner; the same constituting means whereby the vertical movement of the screws 23 in either up or down direction provides means for regulatively tilting or depressing any corner of a given magnet as 9 so as to bring the poles 13—13 into true alinement and juxtapositional proximity with relation to the under part of a companion armature as 8 which extends thereover.

Each end of each individual armature of the said plurality of armatures is provided with a screwthreaded portion 16 that passes through the various post members 7, —7^a, 7^b,

and 7^c in a perforation adjacent the upper end thereof with sufficient end protruding to accommodate a lock-washer as 16^b and an adjustment nut 16^a which constitute means for applying regulative compensative tension to said armature. 70

Said armatures being preferably of flat stock and all of even width but each relatively thicker than the other. Said armatures being supported adjacent the terminations of the flat part thereof by bridge-pieces as 17, said bridges being of suitable height to carry said armature at the proper distance above the pole-pieces 13 to enable said armature to vibrate to and from said poles without making actual contact therewith. 80

It should be understood that the armatures 8^a and 8^c are supported on higher bridge-pieces 17 than are the armatures 8 and 8^b; also, that the portions of all said armatures which extend outwardly from the said bridges deflect at a slight angle to the points 18 where said screwthreaded portions pass through their respective posts 7 so as to pull down on the said respective bridges and thus transmit vibrations from said armatures to the top 4 and also to retain said bridges in their relative positions. 85

It is noteworthy that the sound-hole 5 is of eccentric shape resembling an ovate figure having one flattened side, the object of which is to vary the regional tonal vibrations of the resonator according to the relative distances between any pair of bridges 17 and the edge of said opening. 95

There is great latitude in my reproducing instrument as I am able to govern the sounds emitted therefrom by various adjustments of said bridges and sound posts, by the thicknesses of said armatures and the amount of tensile strain thereto. 100

In order to operate my reproducer it is only necessary to connect all the windings of the electric elements in series and then attach the leads in the manner usual to apparatus of this kind whereby the driving energy is supplied by the audio frequency circuit, which in turn is controlled by the radio energy the specific steps of which are too well known to need detailed explanation. 110

It is believed that the construction, operation and advantages of the invention will now be clearly understood. The present embodiments of the invention have been disclosed in detail merely by way of example, since in actual practice they attain the features of advantage set forth as being desirable in the statement of the invention and the above description. 120

Numerous changes in the details of construction, and in the combination and arrangement of parts may be resorted to without departing from the spirit or scope of the invention as hereinafter claimed or sacrificing any of its advantages. 125

Having thus described my invention, what I claim as new is:—

1. An electromagnetic sound producer comprising a hollow box-like resonant body, a plurality of co-ordinating electromagnetic drivers supported on top of said body, a companion armature for each driver, bridge means for the support of said armatures, adjustable tensing means for tensing said armatures and strain posts to hold the armatures under compensative strain above the level of the points of the strain.

2. An electromagnetic sound reproducer comprising a supporting resonant body carrying a plurality of magnetic elements adapted to drive companion armatures, strain posts carried by said body and adapted to receive the ends of said armatures and hold them under compensative strain while supported on bridge-pieces that elevate said armature above the level of said points of strain.

3. An electromagnetic sound reproducer comprising a resonant supporting body, strain-post means in vertical fixed relation to said body, outer rail means spacing said posts and carried thereby, inner rail means carried by the outer rail means and inmost rail means carried by said inner rail means, said rails being all in the same horizontal plane and adapted to carry magnetic driving means associated with companion armatures.

4. An electromagnetic sound reproducer comprising a resonant body, two parallel armatures carried by the body and axially disposed over two companion magnets energized through the medium of an audio-frequency circuit, a duplicate set of armatures and magnets carried by the body and disposed at right angles to the former, said armatures crossing each other in different planes so as to form a diagrammatic square, and bridge means for the support of said armatures.

5. An electromagnetic sound reproducer comprising a resonant body, sound-posts within the body in vertical proximity to outer bridges said bridges being adapted to support armature means adapted to carry sound vibrations imported by an associated magnet energized through the medium of an audio frequency circuit.

6. In an electromagnetic sound reproducer having a plurality of magnetic elements energized through the medium of an audio-frequency circuit and companion armatures passing thereover, said armatures being mounted by their ends to uprights carried by the body, means for applying strain to said uprights and means coupling said uprights together in pairs at their upper ends for mutual resistance of said strain.

7. In an electromagnetic sound reproducer having a resonant body carrying horizontally-disposed magnet elements energized through the medium of an audio-frequency circuit provided with companion armatures

disposed in a fixed plane, a base means in fixed relation to the said body and means for relatively altering the plane of said magnets with relation to said base and said armature, and for regulating the air-gap between said magnet and said armature.

GEORGE MAEHREN.
